UNITED STATES PATENT OFFICE.

ALFRED T. BALCH, OF BROCKTON, MASSACHUSETTS, ASSIGNOR TO H. F. CRAWFORD MANUFACTURING COMPANY, OF BROCKTON, MASSACHUSETTS, A CORPORATION OF MASSACHUSETTS.

SHANK STIFFENER FOR SHOE SOLES.

Application filed June 23, 1923. Serial No. 647,301.

To all whom it may concern:

Be it known that I, ALFRED T. BALCH, a citizen of the United States, residing at Brockton, in the county of Plymouth and 5 State of Massachusetts, have invented new and useful Improvements in Shank Stiffeners for Shoe Soles, of which the following is a specification.

This application is a continuation in part 10 of my application filed January 2, 1923, Serial No. 610,149.

The invention is embodied in a resilient shank stiffener, adapted to be interposed between the shank portions of the insole 15 and outsole of a shoe, said stiffener having a raised central portion at its inner or upper side normally conforming to the curvature of the shank portion of a last bottom, and yieldingly supporting the shank portion of 20 the inner sole.

The stiffener includes an inner and an outer metal member, and rivets inseparably connecting said members. The inner member is curved, so that it provides the above- 25 mentioned raised central portion of the stiffener. One of the members is slotted to cooperate with one or more of the rivets in permitting a limited sliding movement 30 of the slotted member on the other member, and a downward yielding of the said centrally raised portion of the stiffener.

The desired resilience is provided by 35 making one of said members of tempered steel, adapted to assume a predetermined normal form when released from flexing pressure, and the other of relatively soft steel. The members may have the same normal curvature, so that they contact with each other from end to end, or the inner 40 member may be bowed, so that it contacts with the outer member only at its end portions, and is spaced at its central portion from the outer member, the centrally raised portion of the stiffener formed by the inner 45 member, being, therefore, depressible independently of the portion formed by the outer member.

Other features of construction will be described hereinafter.

50 Of the accompanying drawings forming a part of this specification,—

Figure 1 is a bottom plan view of a portion

of a shoe having a shank stiffener embodying the invention, before the application of the 55 outsole.

Figure 2 is a section on line 2—2 of Figure 1, the outsole being shown by dotted lines.

Figure 3 is a perspective view of the 60 stiffener.

Figure 4 is a plan view showing a modification.

Figure 5 is a section on line 5—5 of 65 Figure 4.

Figure 6 is a plan view showing another 65 modification.

Figure 7 is a section on line 7—7 of Figure 6.

The same reference characters indicate 70 the same parts in all of the figures.

I will first describe the invention as 75 shown by Figures 1, 2, 3, 4 and 5.

My improved stiffener is adapted for use with a shoe, the insole *a* of which has a securing member, such as a bifurcated rivet *b*, inserted in the insole, as shown by Figure 2, the head of the rivet being flush with the upper surface of the insole, and the bifurcations of its shank being bent below the lower surface to form ears *c*, *c* which project 80 in opposite directions and are slightly spaced from the under surface of the inner sole, as shown by the Crawford Patent No. 1,029,278, dated June 11, 1912.

The stiffener comprises an outer member 85 12, which is a thin steel strip, having in its forward end a slot 13, adapted to receive the shank of the rivet *b*, the arrangement being such that the forward end of the member 12 is adapted to slide between the ears *c* and the bottom surface of the insole, as described in the Crawford patent. The opposite end portion of the member 12 may be provided with an orifice 14, adapted to receive a tack 15, driven into the insole, as 90 shown by Figure 2.

The member 12 is curved, to conform to the normal curvature of the shank portion of an outsole *d*.

The stiffener also comprises an inner member 16, which is also a thin strip of steel, and has a more abrupt curvature than the outer member 12, the end portion of the inner member bearing on corresponding por 100

tions of the outer member. The inner member is spaced between its end portions from the outer member, as shown by Figure 2.

The members 12 and 16 are inseparably connected by connections between their end portions, permitting independent flexure of each member, so that the outer member is adapted to conform independently to flexures of the shank portion of the outsole, and the inner member constitutes an independently flexible yielding support for the shank portion of the insole.

Said connections are preferably embodied in headed rivets 17, fixed to one of the members, and passing through the end portions of the other member, the last-mentioned member being slotted to permit independent flexure of each member.

In this instance I show the rivets 17 fixed to the outer member 12, and passing through slots 18 in the inner member, each rivet having a head at one end bearing on one of the members, and an upset end forming another head bearing on the other member.

When the shoe is flexed, as in the act of walking, the outer member is adapted to conform to the flexure, its slotted end sliding in contact with the securing member *b*, and its ears *c*. The inner member 16 may be flexed with the outer member, and is independently flexible and adapted to be pressed at its central portion toward the outer member by the weight of the wearer, the slots 18, and the rivets 17, permitting the described flexures of each of said members.

It will be seen that the inner member 16 constitutes an arch support, which conforms to changes of form of the arch of a human foot, the curvature of the inner member being reduced by an increase of pressure thereon, and restored to normal when the pressure is removed.

Figures 4 and 5 show one slot 18 instead of two, this being formed in the rear end portion of the inner member 16. In other respects the stiffener may be the same as that shown by Figures 1, 2 and 3.

The embodiment of the invention shown by Figures 6 and 7 includes an inner member 20, and an outer member 21, connected by rivets 22. The said members have the same curvature, so that they contact with each other from end to end, instead of being

spaced apart at their central portions. A single slot 23 is provided, this being formed in the outer member 21.

In each embodiment of the invention the resilience of the stiffener adapting it to be flexed from its normal curvature and to return thereto, is provided by making one of the members of tempered steel and the other of relatively soft steel. The tempered member, which may be the member 16 shown by Figures 1 to 5, and the member 21 shown by Figures 6 and 7, may be shorter, and is preferably somewhat thicker than the other member 12 or 20. The tempered member and the rivets maintain the softer member at a suitable curvature. The cost of manufacture is thus materially reduced, and the expense involved in tempering one of the members eliminated, the decreased length of the tempered member effecting a saving of material.

In assembling the members I space the ends of the shorter member from the ends of the longer member, so that the latter presents two end extensions of single thickness at the opposite ends of the stiffener, one of these extensions containing the slot 13, and the other the orifice 14. The devices which secure the stiffener to the inner sole, therefore, engage only the said extensions.

I claim:

A resilient shank stiffener adapted to be interposed between an outer and an inner sole and comprising an outer and an inner metal member, and rivets inseparably connecting the same, said members being curved so that the under side of the stiffener has a centrally raised portion which conforms to the curvature of the shank portion of a last bottom, one of said members being slotted to permit a limited sliding movement thereof on the other member, and a downward yielding of the centrally raised portion, one of said members being of steel, tempered to impart suitable resilience to the stiffener, and the other of relatively soft steel, maintained at the desired curvature by the tempered member and the said rivets.

In testimony whereof I have affixed my signature.

ALFRED T. BALCH.
